(57) **CLAIM**

I claim the ornamental design of the handle for bag, as shown and described.

DESCRIPTION

FIG. 1 is a front elevational view of one embodiment of a handle for a bag showing the design of the present invention.

FIG. 2 is a top side view thereof; and,

FIG. 3 is an end view thereof.

The broken lines shown in FIGS. 1-3 are for illustrative purposes only and form no part of the claimed design.

1 Claim, 2 Drawing Sheets

FIG. 1

FIG. 2

FIG. 3
